UNITED STATES PATENT OFFICE

ROGER S. STOCKDALE, OF MILWAUKEE, WISCONSIN

DESIGN FOR A SIGN

Application filed November 12, 1928. Serial No. 28,851. Term of patent 3½ years.

To all whom it may concern:

Be it known that I, ROGER S. STOCKDALE, a citizen of the United States, residing at Milwaukee, in the county of Milwaukee and State of Wisconsin, have invented a new, original, and ornamental Design for Signs, of which the following is a description, reference being had to the accompanying drawing, forming part thereof.

In the drawing:

Fig. 1 is a front view of the sign showing my new design, with the side portions thereof lined to indicate green and the upper end portion thereof lined to indicate red; and

Fig. 2 is a plan view of the sign.

I claim:

The ornamental design for a sign, as shown and described.

ROGER S. STOCKDALE.
